CLAIM

The ornamental design for a pet dental treat, as shown and described.

DESCRIPTION

FIG. 1 is a front, top and left side perspective view of a pet dental treat according to our new design;

FIG. 2 is a top plan view thereof;

FIG. 3 is a bottom plan view thereof;

FIG. 4 is a rear elevation view thereof;

FIG. 5 is a front elevation view thereof;

FIG. 6 is a left side elevation view thereof; and,

FIG. 7 is a right side elevation view thereof.

The broken lines shown in FIGS. 1–5 illustrate portions of the pet dental treat that form no part of the claimed design.
